Primary Examiner — Jack Reickel*Assistant Examiner* — Christopher M Spivey(74) *Attorney, Agent, or Firm* — JCIPRNET**CLAIM**

The ornamental design for a display screen or portion thereof with graphical user interface, as shown and described.

DESCRIPTION

FIG. 1 is a front view of a display screen or portion thereof with graphical user interface according to a first embodiment of our new design; and,

FIG. 2 is a front view of a display screen or portion thereof with graphical user interface according to a second embodiment of our new design.

The dot-dash broken lines showing the display screen or portion thereof in FIGS. 1-2 form no part of the claimed design. The dashed broken lines showing portions of the graphical user interface in FIGS. 1 and 2 form no part of the claimed design.
